GOLF CLUB HEAD

George A. Phillips, 2888 Cataract Place, El Cajon, Calif.

Filed Mar. 4, 1964, Ser. No. 78,875

Term of patent 14 years

(Cl. D34—5)

FIG. 1 is a perspective view of my new design for a golf club head.

FIG. 2 is a rear view of the golf club head.

FIG. 3 is an end view taken from the right hand end of FIG. 2.

FIG. 4 is a view of the strike face of my golf club head.

FIG. 5 is a top plan view.

FIG. 6 is a bottom plan view of my golf club head.

The broken line showing of the shaft in FIG. 1 is for illustrative purposes only.

I claim:

The ornamental design for a golf club head, as shown and described.
